UNITED STATES PATENT OFFICE.

REUBEN H. HARPER, OF CHICAGO, ILLINOIS.

ADJUSTABLE THREAD CUTTER.

Application filed July 7, 1921. Serial No. 483,107.

To all whom it may concern:

Be it known that I, REUBEN H. HARPER, a citizen of the United States, residing at Chicago, in the county of Cook and State of Illinois, have invented certain new and useful Improvements in an Adjustable Thread Cutter, of which the following is a specification.

This invention relates to a threading tool which is adapted to be used for separately cutting a number of different threads with the same tool. One of the principal objects of the invention is to provide improved means for setting the tool to make a light 10 or a deep cut, and to vary the adjustment so that threads of different sizes but of the same pitch can be cut with the same dies. A further object of this invention is to provide improved means for connecting the sections 20 of the tool. A still further object is to provide a construction which can be folded in compact form.

In the accompanying drawing, Fig. 1 is a plan view of a tool constructed in accordance 25 with the principles of this invention; Fig. 2 is a section taken on the line 2—2 of Fig. 1; Fig. 3 is an end view; Fig. 4 is an enlarged view with part broken away showing the adjustment at the hinged end of the 30 tool; and Fig. 5 is a view showing the adjustable locking means at the other end of the tool.

This tool comprises a pair of members having co-acting die faces on opposite sides 35 of each member, the corresponding pairs of which may be brought together by a pivotal mounting at one end and locked in position by an adjustable clamping device at the other end. In order to set the co-acting die 40 faces, a careful adjustment of the members is necessary and the adjustment must be in a parallel direction. It is therefore necessary to provide an adjustment in the hinge and also an adjustment in the clamping 45 device.

Referring more particularly to the drawings, a pair of members 1 and 2 are connected at one end by a hinge 15 and at the other end by a clamping device 4. In the opposite 50 edges of each member are recesses for seating co-acting die plates 5 and 6, and 7 and 8. Either pair of dies may be brought into co-acting engagement by rotating the members 1 and 2 about their hinge.

At the opposite ends of the members 1 and 2 are slotted projections 9 with a cou-

pling 10 pivoted therein which has a short threaded stem 11 upon which a handle 12 may be secured. When the handle is threaded up tight against the outside of the projections 9, as shown in Fig. 1, it is in position for use, but by backing the handle off on the threaded stem, the handle 12 and its coupling 10 may be rotated to the broken line position 12^a and then the handle is threaded up against the inside of the projections 9 for folding the tool compactly.

In the corresponding edges of the members are alining pins 13 and recesses 14 for receiving them.

The corresponding ends of the members 1 and 2 are slotted to receive a hinge plate or link 15, or a plurality of plates to make up the desired thickness, and in this plate is an opening 16 to receive a threaded member 17 which has a head 18 with a transverse hole 19 to receive a pivot screw 20 which extends through the slotted end of the member 1. An adjusting nut 21 is mounted on the member 17 and adjusts the position 80 of the pivot screw 20 with respect to the link 15. Another pivot screw 22 directly connects the link 15 with the member 2.

In the opposite edges of the link 15 adjacent the adjustable end are graduated 85 marks 23 which register with a pointer 24 in the member 1 formed by boring two holes 25 close together, so that they partially overlap and by counter-boring the upper edges of these holes to make the extremity of the 90 pointer more distinct. With this graduation and pointer it is possible to make a very close adjustment of the hinged end of the tool. In fact, this enables the tool to be set for a deep or a slight cut as desired, or to 95 cut a thread of the same pitch upon members of different sizes, within the limits of the graduation.

The clamping device comprises an apertured link 4 pivoted to a projection 25' on 100 one of the members and extending over a projection 26 on the other one. Between the projections is a partition 27 through which a bearing pin 28 extends loosely having a head 29 at one end to engage one side of the projection 26, and an enlargement 30 at the other end to prevent the disengagement of the pin, and a spring 31 tending to force the head into engagement with the projection 26. At the outer end of the link 105 32 is an adjusting screw which may be threaded inwardly against the opposite face

of the projection 26 so that by threading the screw 32 inwardly or outwardly the member 2 is adjusted and held in place by the spring 31 so that it is held parallel with the adjustable hinge. A mark 33 is provided on the link 4 and a corresponding graduation 34 is made in the edge of the member 2 so that the clamping device may be adjusted to correspond with the hinged adjustment 10 at the other end.

With this construction it is obvious that the tool may be accurately set not only for different depths of cut for the same thread, but also for threads of the same pitch and different diameters of thread. The adjustment may be made quickly and easily, and in order to change the tool to use the opposite set dies it is necessary only to release the clamping device by turning the screw 20 32 or pressing the member 2 inwardly at this end, to swing the clamping device out of engagement with the projection 26 and to swing the members 1 and 2 about their hinge until the other set of dies is brought 25 into co-acting position.

I claim:

1. A thread cutter comprising a pair of members having co-acting die faces on opposite sides and a pivotal connection for one 30 end of said members, and means including a part of said pivotal connection for regulating the separation of the members, said means comprising an adjusting nut and screw and a link in which they are movable.

2. A thread cutter comprising a pair of members having die faces on opposite sides, a plate pivoted to one of the members and having a recess therein, an adjusting nut and a screw therefor seated in the recess in 40 the plate and the screw pivoted to the other member.

3. A thread cutting tool comprising a pair of co-acting members with corresponding slotted extremities, an apertured hinge 45 therefor seated in the slots of the extremities and directly pivoted to one of the members, an adjusting nut and a screw disposed in the aperture of the hinge, the screw being pivotally connected to the other of said 50 members, and movable lengthwise in the hinge by the rotation of the nut, the slotted portions of the members retaining the nut and screw in the hinge.

4. The combination in a thread cutting 55 tool, of a pair of members having opposite co-acting faces, a hinge therefor comprising an apertured plate attached to one of the members and an adjusting nut and screw movable in the aperture of the plate and attached to the other member, and an adjustable clamping means for the ends of the members opposite the hinge.

5. The combination with a pair of members having co-acting die faces on opposite

sides, of an adjustable hinge therefor comprising an apertured plate pivoted to one of the members, the adjusting nut and screw movable in the aperture and the screw pivoted to the other member, means for holding the members parallel to each other, and a clamping device opposite the hinged ends of the members adapted to vary the distance apart of the members at this end.

6. In a tool of the class described, a pair of members having adjustable hinge connection at one end, means for holding the members parallel for moving them forward and from each other, and an adjustable clamping device for the device at the ends opposite the hinge, said clamping device comprising an apertured link hinged to one of the members and extending over a projection of the other, a spring pressed abutment to engage one side of the projection and the adjusting screw to engage the other side of the projection.

7. In a hinged tool, a pair of members, a hinged plate pivoted to one of the members, means forming an adjustable connection movable with respect to the plate and pivoted to the other member, graduations on opposite sides of the hinge plate, and a pointer on the member to which the hinge plate is not directly pivoted corresponding to the graduations at the sides of the hinge plate.

8. A tool comprising a pair of members having co-acting die faces on opposite sides, an adjustable hinge therefor comprising a plate directly pivoted to one of the members, and means movable with respect to the plate and pivotally connected to the other member, graduations on opposite sides of the plate at the end which is not directly pivoted to one of the members, and a peep-sight having a projection therein forming a pointer in the member to which the plate is not pivotally connected, the pointer corresponding to the graduations on either side of the plate for the adjustment of the members for either pair of co-acting die faces.

9. A tool comprising a pair of members having co-acting die faces on opposite sides, an adjustable hinge at one end of the members, a clamping device at the other end of the members, and a pair of foldable handles for the members comprising an upstanding slotted portion at one end of each member, a coupling pivotally connected therein, and a handle threaded upon the coupling and movable thereon against either side of the projection, extending from the member when abutting the outside of the projection and extending over the member in compact folded position when abutting the inside of the member.

REUBEN H. HARPER.
